UNITED STATES PATENT OFFICE.

BELLE GOODRICH AND THOMAS E. GOODRICH, OF SHELBYVILLE, INDIANA.

GOSSAMER CLOAK.

SPECIFICATION forming part of Letters Patent No. 353,743, dated December 7, 1886.

Application filed April 29, 1886. Serial No. 200,516. (No model.)

To all whom it may concern:

Be it known that we, BELLE GOODRICH and THOMAS E. GOODRICH, citizens of the United States, residing at Shelbyville, in the county 5 of Shelby and State of Indiana, have invented certain new and useful Improvements in Water-Proof Garments; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Our invention relates to that class of apparel known as "water-proof circulars or gossamers," and particularly to such as are adapted to be worn by ladies; and it consists in the construction, arrangement, and combination of the various parts, as will be hereinafter fully described.

25 In the accompanying drawings, illustrative of our invention, Figure 1 is a view in front elevation of the interior of our improved circular. Fig. 2 is an enlarged detail representation of the series of folds or plaits in the rear portion of the garment, and Fig. 3 is a cross-section of the same on the line xx of Fig. 2.

Similar letters of reference denote corresponding parts throughout all the figures.

30 A represents a waterproofed covering or wrap, and B B the armholes located at the proper points therein.

C designates a belt, made of any suitable material and of any size, and adapted to encircle the waist of the wearer of the garment and be firmly secured at its meeting ends by a buckle or other equivalent fastening device. This belt is secured to the inner rear part of the 35 water-proof garment, preferably by means of two straps, $a a$, firmly attached to the belt and likewise to the substance of the garment. Further, the belt is provided with depending straps D D, attached thereto at convenient 40 points. These straps are made in two parts, which are buckled or otherwise adjustably connected together, so that the straps may be lengthened or shortened. At the lower end they are provided with hooks d .

45 The belt C and its extensible depending straps D D, carrying hooks at their lower ex-

tremity, constitute a means for supporting the skirts of the wearer's dress, for it will be evident that when the person has donned the waterproofed garment the belt C may be secured 55 about the waist, the straps D be lengthened or shortened in the proper manner, and the hooks or other devices d , be inserted into the dress or under-garments, so as to uphold them entirely off the ground and above the bottom of the 60 circular, thus keeping them from being bedraggled with mud and water. The straps may be few or several in number, it being only necessary that there should be enough to support the bottom of the dress throughout its 65 whole length.

The armholes B B are provided with strengthening guards or gussets b , for the purpose of preventing the ripping or tearing of the material at these points. These gussets 70 consist of pieces of cloth cut into angular, triangular, semicircular, or other shape, and inserted by stitching or otherwise at the top and bottom of the arm-openings. Either one or both of the pieces b in each armhole is looped 75 or made longer than the width of said armhole, to permit of the easy expansion of the latter during the placing of the arms through the hole.

The middle of the rear portion of our improved circular is formed with a series of plaitings, E, made by the folding of the material, as shown in Figs. 2 and 3. These folds extend from the bottom of the circular to within a greater or less distance from the top. In the 80 drawings the folds or plaits extend from the bottom to near the point where the belt is attached. This arrangement imparts a fullness to the garment which prevents it from cupping in about the feet, and thereby prevents the 85 soiling or wetting of the hosiery, shoe-tops, or under-garments. It also admits of the freest action of the lower limbs in getting into or alighting from a vehicle, ascending or descending stairs, stepping across open gutters, &c. 90 Further, when the garment fills with wind, instead of pulling in about the feet and binding against them, as is customary with the usual construction, it spreads, and thus turns the water out. When the back of a water-proof 95 garment is constructed in this expandible way, a person can more easily wear wraps of vary-

ing size, and the fullness of the skirt thus obtained permits the dress or under-garments being looped up by the devices above described, and when they are so raised the water-proof is held out free from contact with the remainder of the clothing.

Having thus described our invention, what we claim as new, and desire to secure by Letters Patent, is—

- 10. The combination of the main part A of the circular, provided with a series of plaits, E, along the middle of the rear portion, and the

device for supporting the dress, consisting of the belt C, secured to the said part A, and the depending adjustable straps D, attached to the belt C and provided with hooks, substantially as shown and described.

In testimony whereof we affix our signatures in presence of two witnesses.

BELLE GOODRICH.

THOMAS E. GOODRICH.
